UNITED STATES PATENT OFFICE.

WARREN TRAVELL, OF RIDGEWOOD, NEW JERSEY.

HOISTING AND TRANSPORTING MECHANISM.

1,184,051.

Specification of Letters Patent. Patented May 23, 1916.

Application filed February 2, 1915. Serial No. 5,635.

To all whom it may concern:

Be it known that I, WARREN TRAVELL, a citizen of the United States, residing at Ridgewood, in the county of Bergen and 5 State of New Jersey, have invented new and useful Improvements in Hoisting and Transporting Mechanism, of which the following is a specification.

This invention relates to improvements in 10 hoisting and transporting mechanism.

More particularly it relates to apparatus in which the load is raised or lowered and transported by the revolution of a drum around which the operating ropes pass, and 15 is more or less balanced by a counterweight.

It is an object of the invention to simplify apparatus of this character, especially by making a single rope serve purposes for 20 which two have sometimes hitherto been required; to provide for the transportation of a load by the same single rope which has elevated it without the necessity of the transportation going up an incline, which has 25 characterized some types of apparatus heretofore designed for working with a single rope; to do this with either a hand-operated or an automatic shift between the elevating and the transporting movement; to provide 30 means for controlling easily the elevation at which the shift occurs; to provide a further controlling means, supplementing the action of a counterweight and therefore reducing the work required of the hoisting engine, effecting a material saving both in first 35 cost of apparatus and in operating expense, which is accomplished by means of a suitable clamping device; and in general to provide apparatus and combinations having the other advantages and improvements that 40 characterize the invention herein set forth.

It is the object of the patent to cover, by suitable expression in the appended claims, whatever features of patentable novelty exist in the invention disclosed.

In order to give a practical understanding 45 of the invention, an embodiment of it in one particular type of apparatus is described and illustrated herein; but it will naturally be understood that the invention may be embodied in many and various forms without departing from the scope of the patent.

In the accompanying drawing: Figure 1 50 illustrates, somewhat diagrammatically, an embodiment of the invention as it may be arranged for unloading a vessel; Fig. 2 is a side elevation of a detail on an enlarged

scale; Fig. 3 is a diagrammatic representation of another embodiment of the invention; Fig. 4 is an elevation representing a device that may be used for operating the 60 clamps upon certain ropes shown in Fig. 3; Fig. 5 is a plan of the same, in section on the line 5—5 of Fig. 4; Fig. 6 represents, on an enlarged scale, the drum shown in Figs. 1 and 3.

In the accompanying drawing the reference numeral 1 indicates a track or way supported in mid-air by any suitable means, here represented by the supports marked 4. This way may be of any type, with rails or 70 cable or other guides, horizontal or inclined and may extend to any desired distance. It may have an extension to reach over water or roadway which is here represented as a boom 2, capable of being swung on hinges 75 between the full line position and the dotted line position, by a winch 6 from which a rope 7 leads over sheaves 8 and 9 to the boom. The boom may be made and mounted so that it is retractable according to any 80 suitable construction, its particular purpose being to project the way beyond its last support to a place where it is desired to manipulate a bucket or other load 16. In the particular representation made in the drawings such a bucket is portrayed as being controlled by a drum 10, operated by an engine 11, from which drum a rope 12 leads over a fixed sheave 13, and a sheave 14 on a carriage 25 to the bucket or other load 16. In 85 the particular form illustrated this rope passes down, around a sheave 15 at the load, and up again to the carriage 25 to which its end is fastened. It will be readily understood, however, that other arrangements of 90 tackle supporting the load on the end of this rope may be adopted without departing from the scope of the invention, according as may be convenient or desirable. From the same drum 10, but wound on the drum 95 in the opposite direction, a rope 23 extends, passing from the drum 10 and around a traveling sheave 20, a fixed sheave 19, and thence going by any convenient path such as the fixed sheave 18 to a sheave 17 at the extreme end of the extension 2, and around that sheave to the carriage 25, to which it 100 is attached so as to pull the carriage in the opposite direction from that in which the rope 12 would pull it. In effect this rope 23 105 is continuous with the rope 12 at the drum 10, although as a matter of construction it

may be either actually continuous with it or separate from it. Fig. 6 shows an advantageous arrangement, where two separate ropes are attached one to each end of a single drum. Being attached to the same drum they must work as if they were one, but the advantage is attained that the same winding space is used for each of them. The reference herein to the ropes 23 and 12 10 as being continuous must therefore be understood as meaning continuous in effect, however that effect may be attained.

The traveling sheave 20 is connected with a counterweight 22 by a rope 31 passing 15 over a fixed sheave 21. As illustrated in Fig. 1, this counterweight and sheave travel reciprocally in vertical paths; and a stop 26 is provided in such position as to determine the lower limit of travel of the counterweight 22, thus determining the upper 20 limit of travel of the sheave 20. Fig. 3 illustrates a case where the counterweight and the sheave 20 travel in the same direction. The direction is immaterial, the important 25 feature being that the counterweight imposes a pull on the rope 23 and the engine drum 10 opposing the pull of the rope 12 on the carriage 25 and the engine drum 10.

30 24 is a stop which limits the travel of the carriage 25 in the outward direction on tracks 1, 2. The stops 24 and 26 may be fixed, or may be adjustable in position, so as to bring the carriage and the counterweight 35 respectively to a stop at places different from those illustrated; and these stops may be constructed according to any suitable design. In the drawing, the stop 26 is diagrammatically represented as being adjustable. Dotted lines show the positions of the counterweight with its attached sheave and ropes when they are at their limit as determined by the position in which the stop 26 is put. When the various parts constituting 40 the invention are arranged in the position shown in full lines in Fig. 1, the counterweight is exerting an upward pull on the sheave 20 and through that by one branch on the drum 10 and by another branch on 45 the carriage 25. The pull on the drum 10 is opposed by the brake on that drum, or by the engine connection; or, assuming that the engine be disconnected and that there be no brake, is opposed by the weight of the 50 load 16, tending to pull the rope 12 in the direction opposite to that shown by the arrow thereon. Hence in a static position either the brake or the engine or the load, or any or all of them combined, hold fast the 55 part of rope 23 which is on the drum; and the counterweight 22 pulling upward on sheave 20 takes up all slack and holds the carriage 25 pulled firmly outward in whatever position its further movement is barred 60 by a stop 24 or by any other means.

Revolution of the drum 10 over to the right as represented in the drawing, maintains this situation, the load 16 being raised from position A gradually, and the sheave 20 rising and taking up the slack let out by 70 the drum 10, while the counterweight 22 is descending. However, when the counterweight 22 has reached its support 26, it no longer tends to move the sheave 20 upward but merely holds it from descending; it can 75 take up no more slack; when the continued revolution of drum 10 pays out more of rope 23 the outward pull on carriage 25 is released; and since the rope 12 is pulled in by the drum just as fast as the rope 23 is 80 paid out by it, the system yields or slips at the point of least resistance and the carriage 25 moves to the left on the tracks 2, 1. The alternative to this would be for the raising 85 of the load 16 to continue; but obviously under all ordinary conditions it would require more power to raise that load than to pull the carriage 25 on its track. Hence when the counterweight has reached its stop 26 the action automatically changes, the load 90 ceasing to rise but acting to hold tight the loop of rope which is below the sheave 14, while the carriage moves inward, being drawn by rope 12 and followed by rope 23 at the same rate. The position of the load 95 at the instant of this change is indicated by the dotted lines at B. This travel may continue until any desired position is attained, as indicated, for example, by the dotted lines at C, where the load may be discharged 100 either automatically by any suitable means or by hand. If it is desired to lower the load at that place a stop here represented as a pawl 27 may be put in position to hold the carriage against movement in the reverse direction outward along the track; and then upon reversal of movement of the drum the load will descend from C toward the dotted 105 position D as the rope 12 is paid out from the drum. Simultaneously, the draft of the 110 drum on the rope 23 will pull the sheave 20 down, raising the counterweight 22, because the end of rope 23 is stayed at 27. To raise the load or the empty bucket from position 115 D the action is the same as for raising it from position A: the drum is turned over to the right, drawing in rope 12 and paying out rope 23, the sheave 20 co-incidently rising and the counterweight 22 descending. When the descent of the counterweight has 120 been stopped, the load being then at the level C, the action will automatically shift to a horizontal movement of the carriage, which will be to the left, because of the direction 125 in which the drum 10 is turning; but by reversing the engine at this instant and removing the stop 27 the carriage will be moved to the right until the stop 24 is encountered, when, upon the staying of rope 130 23, the continuing draft by drum 10 will

draw down the sheave 20, raising the counterweight 22, while the paying out of rope 12 allows the bucket or load 16 to descend to its initial position A where the described 5 cycle of operations began. It is of course assumed that a counterweight of suitable size is used, having regard to the weight of load 16, and that the engine 11, or some other suitable means, together with the friction 10 of the rope, acts as a brake to control the speed or to hold the parts stationary, against any preponderance, either of counterweight or of load.

Apparatus of the variety indicated in 15 Fig. 1 can be used with high economy for many commercial purposes because the track can extend inward to any desired distance, approximately horizontally, and the bucket may be raised no higher than necessary for 20 the dumping, and the shift from elevating to transporting or the reverse is automatic and therefore speedy, and is effected without stopping and re-starting the engine. Thus the bucket may be loaded in the bottom 25 of the vessel, raised to the level of the position D, its motion automatically converting from an elevating to a transporting movement and then running in to the position D. After dumping, a simple reversal 30 of the engine carries it back and down again to the position A. The elevation at which the change between the vertical and the horizontal movement of the load automatically occurs is determined by the elevation 35 at which the descent of counterweight 22 is stopped. The position at which the descent of the bucket or load from the carriage begins is determined by the position where its outward movement on the track is stopped 40 while the drum 10 continues to pay out rope 12. Such stoppage of the carriage may be accomplished by any suitable means such, for example, as a device arranged on the carriage itself, such as a pawl 27 adapted 45 to engage a fixed rack 28 beside the track. As illustrated this pawl is normally kept out of engagement by a spring, but may be drawn into engagement by a rope 30 so as to prevent movement of the carriage outward. 50 When thus drawn into engagement the engine may be reversed and the load lowered by merely reversing the engine. The pawl is automatically released whenever the pull on rope 30 is released, and rotation 55 of the engine in the backward direction under those circumstances will move the carriage outward again. For the operation of apparatus for unloading from a vessel, such as that illustrated, a fixed stop 60 24, properly positioned, may conveniently be used as this causes the shift at the proper place without attention of the operator.

Other applications of the invention may be made; and variations from the particular arrangement illustrated may be made

without departing from the scope of the invention as defined in the accompanying claims. In particular the number of possible variations of the manner of reeving the ropes is very great; and the manner of stopping the counterweight and the carriage, as illustrated, are to be considered as diagrammatic.

Instead of using stops 24 and 27 to limit the travel of the carriage similar results 75 may be obtained by applying a stop such as a clamp, friction drum, or other device to the rope 23 at any point of its length between the sheave 20 and the carriage 25. Similarly the support for the counterweight 80 22 is not necessarily a platform support as illustrated, but may take the form of any kind of a contrivance acting either on the rope 31 or on the counterweight to prevent further descent of the counterweight. 85

In Fig. 1, 26' and 27' indicate diagrammatically, places where clamps might be applied to seize and hold the rope 31 supporting the counterweight and the rope 23. However, the apparatus illustrated in that 90 figure is complete without such clamps, and the clamps if present would be additional or alternative to other means shown in that figure. Fig. 3 illustrates a different style of reeving the ropes, an electric motor 11' 95 instead of the engine 11 for operating the drum 10, a sheave 20' corresponding to the sheave 20 of Fig. 1, and a counterweight 22' of adjustable weight connected with the sheave 20' by a rope 31' which passes around two sheaves, 19 and 19', so that downward movement of the counterweight corresponds with downward movement of the sheave 20'. This general arrangement permits convenient assemblage of the clamps 26', 27', 100 applied respectively to the ropes 31' and 23, the motor and the drum all within reach of the controlling operator. Fig. 4 illustrates in detail an appliance (which is shown on a smaller scale in Fig. 3 and is suggested 110 diagrammatically in Fig. 1) for controlling such clamps and guarding against both being worked at the same time. As there seen, a lever having a handle 59 can be thrown in one direction to clamp the rope 115 31' between the shoes 26' and 66, or in the other direction to clamp the rope 23 between the shoes 27' and 67. In the construction represented, there are cross beams 61 fixed rigidly on the supporting frame, holding a 120 fixed fulcrum 58 on which the lever 59 may be swung in order to compress the shoe 26' against a stationary shoe 66, rigidly supported upon the said beams 61. This clamps the rope 31 between these two shoes and at 125 the same time pushes the shoe 27' away from the fixed shoe 67 so that the rope 23 runs free. Swinging the lever in the opposite direction produces the opposite effect, clamping rope 23 and leaving rope 31' free; 130

but both ropes cannot be clamped at the same time. This rope clamping apparatus may obviously supplant the stop 26 of Fig. 1, because by throwing the lever 59 in the proper direction the operator can stop a counterweight 22' at any point in its descent as effectively as by the use of a stop of the type shown at 26 in Fig. 1; and likewise by throwing the lever 59 in the opposite direction movement of the rope 23 can be arrested as effectively as by the use of a stop of the type 24 or 27 of Figs. 1 and 2. Either of these clamps can hold its rope firmly so as to resist a pull greater than the weight of the counterweight if such effect ever be wanted, in which case it would have the effect of temporarily supplementing or supplanting the counterweight.

In the operation of the device the effect of friction is an important factor. In a machine constructed and operated under ordinary commercial conditions there will be a substantial degree of friction at each sheave; and this always tends to prevent motion. Hence, for example, if there be a bucket 16 weighing 1000 pounds and having capacity for a load of 2000 pounds, and a counterweight of 2000 pounds, the apparatus will stay in equilibrium even when the full load of 3000 pounds is suspended stationarily in mid-air, the load not descending or moving the carriage inward notwithstanding that it exceeds the counterweight by a thousand pounds. On the other hand, the apparatus will equally stay in equilibrium when the bucket is empty and the counterweight exceeds the load suspended from the carriage by a thousand pounds. This illustration is figured on an allowance of 10 percent. for friction at each sheave and shows how there may be equilibrium against motion for all loads between 1000 and 3000 pounds with a single counterweight. If in any case friction of the engine be included in the computation the range of equilibrium under variations of loading will be found to be greater. With additional sheaves a still greater range is obtainable. It is believed that in most cases arising in actual practice the whole mechanism will always be in balance, whether loaded or unloaded, with only such sheaves as are necessary for the proper guidance of the ropes, so that a friction brake on the engine will not be necessary, or if present need not be used. A clamping arrangement can therefore be conveniently used, such as that illustrated, by which either rope alone may be clamped, or neither of them, at the will of the operator. The condition of equilibrium and the avoidance of the necessity of using friction brakes are regarded as features of importance in the invention. In large machines where the variation of loading is considerable, friction brakes on

the engine may be desirable, and it may also be desirable to provide them for use in emergencies, even though not necessary in the ordinary operation of the system.

The invention herein disclosed can be applied in many and various forms, as will be readily understood by those skilled in dealing with hoisting and transporting mechanism, differing much in appearance perhaps from the particular forms here illustrated, while still utilizing the benefits of the discovery which I have made and hereinbefore set forth. It is intended that the patent shall cover by suitable expression in the appended claims whatever features of novelty exist in the invention disclosed.

I claim:

1. The combination, with a way, a carriage, a combined traverse and hoisting rope extending along the way to and depending from the carriage, and means to control motion of that rope; of a second rope extending from said control means as a continuation of the first rope and reaching the carriage from a direction opposite to that of the first rope; a counterweight holding taut an extensible loop in the second rope; means to stop the carriage positively from moving in the direction of pull of the second rope when the depending rope is below its extreme upper position; and means to stop descent of the counterweight, whereby the loop ceases extending and the second rope pays out the carriage.

2. The combination, with a way, a carriage, a combined traverse and hoisting rope extending along the way to and depending from the carriage, and means to control motion of that rope; of a second rope extending from said control means as a continuation of the first rope and reaching the carriage from a direction opposite to that of the first rope; a counterweight holding taut an extensible loop in the second rope; means to stop the carriage positively from moving in the direction of pull of the second rope when the depending rope is below its extreme upper position; and means to stop descent of the counterweight, whereby the loop ceases extending and the second rope pays out the carriage; the counterweight, reeving and friction being such as to produce at the carriage a resistance to traverse movement overcoming the tendency to traverse movement resulting from the depending load.

3. The combination, with a way, a carriage, a combined traverse and hoisting rope extending along the way to and depending from the carriage, and means to control motion of that rope; of a second rope extending from said control means as a continuation of the first rope and reaching the carriage from a direction opposite to that of the first rope; a counterweight holding taut an

- extensible loop in the second rope; means to oppose with an equal force the component of the counterweight's pull which might move the carriage, leaving the apparatus 5 free for hoisting; and means barring descent of the counterweight beyond a predetermined point, whereby the loop ceases extending and the ropes operate the traverse action.
- 10 4. In apparatus of the class described the combination, with a movable carriage, of a rope for hoisting and traversing, a rope continuation thereof attached to and adapted to pull the carriage in a direction opposing the pull of the first rope thereon, means to absorb rope in the hoisting action and means to stop such absorption automatically at a predetermined point, thereby making a traverse action.
- 15 5. In apparatus of the class described, the combination with a movable carriage, of a rope for hoisting and traversing, a rope continuation thereof attached to and adapted to pull the carriage in a direction opposing the pull of the first rope thereon; a lug on the carriage, movable with respect thereto, and adapted to engage a stationary part to stop movement of the carriage and means to absorb and pay out the rope for the hoisting 30 action while movement of the carriage is stopped.
- 20 6. In apparatus of the class described the combination, with a movable carriage, of a rope for hoisting and traversing, a rope continuation thereof attached to and adapted to pull the carriage in a direction opposing the pull of the first rope thereon; a stationary lug adapted to engage the carriage in opposition to the pull of the continuation rope 35 with equal force, whereby the carriage ceases its traverse movement; and a counterweight holding taut an extensible loop in said continuation rope, absorbing slack thereof during the hoisting action.
- 25 7. In apparatus of the class described the combination, with a movable carriage, of a rope for hoisting and traversing, a rope continuation thereof attached to and adapted to pull the carriage in a direction opposing the pull of the first rope thereon; a stationary lug adapted to engage the carriage in opposition to the pull of the continuation rope, whereby the carriage ceases its traverse movement; a counterweight holding taut an extensible loop in said continuation rope, absorbing slack thereof during the hoisting action; and a supporting platform for the counterweight stopping extension of said loop at a predetermined point, whereby the 40 hoisting action ceases.
- 30 8. In apparatus of the class described the combination with a movable carriage, of a rope for hoisting and traversing, extending from the hoist at the carriage along its way and around to the carriage again and at-
- tached thereto from the opposite direction; a loop in the rope; another rope for pulling the loop taut; frictional clamping means applicable to each of said ropes and a single lever and connections whereby movement 70 thereof in either direction releases one clamp and sets the other.
9. In apparatus of the class described the combination, with a movable carriage, of a rope for hoisting and traversing, extending 75 from the hoist at the carriage along its way and around to the carriage again and attached thereto from the opposite direction; a loop in the rope; means for pulling the loop taut; frictional clamping means applicable to said pulling means and said rope, adapted to balance the pull of either; and actuating means for the rope applied between said loop and hoist.
10. In apparatus of the class described, 85 the combination, with a movable carriage, of a rope for hoisting and traversing, a rope continuation thereof attached to and adapted to pull the carriage in a direction opposing the pull of the first rope thereon, a rope 90 arranged to absorb and pay out rope in the hoisting action; and two clamps, one applicable to said absorption rope thereby producing the traverse action, and the other applicable to said continuation rope thereby 95 producing the hoisting action.
11. In apparatus of the class described, the combination, with a movable carriage, of a rope for hoisting and traversing, a rope continuation thereof attached to and adapted to 100 pull the carriage in a direction opposing the pull of the first rope thereon, a rope arranged to absorb and pay out rope in the hoisting action, two clamps, one applicable to said absorption rope thereby producing 105 the traverse action, and the other applicable to said continuation rope thereby producing the hoisting action; and means to apply either one of these clamps and thereby release the other. 110
12. In apparatus of the class described, the combination, with a movable carriage and a guideway for it, of a rope for hoisting and traversing, extending from the hoist at the carriage along its way and around till 115 it reaches the carriage from the opposite direction; a loop in the rope, extending and contracting with the hoisting action; a power-applying device adapted to extend the loop and means acting automatically at 120 a predetermined point to stop such extension whereby continuation of movement of the rope produces a traversing action.
13. In apparatus of the class described, the combination, with a movable carriage 125 and a guideway for it, of a rope for hoisting and traversing, extending from the hoist at the carriage along its way and around till it reaches the carriage from the opposite direction; a loop in the rope, extending and 130

contracting with the hoisting action; a counterweight tending to extend the loop and automatically acting means to arrest descent of the counterweight at a predetermined point, whereby the action is automatically converted from hoisting to traversing at a predetermined elevation of the load.

14. The combination, with a way, a carriage, a combined traverse and hoisting rope extending along the way to and depending from the carriage, and means to control motion of that rope; of a second rope extending from said control means as a continuation of the first rope and reaching the carriage from a direction opposite to that of the first rope; a counterweight holding taut an extensible loop in the second rope; means other than said rope to stop the carriage from moving in the direction of pull of the second rope; and means to stop descent of the counterweight, whereby the loop ceases extending and the second rope pays out the carriage.

15. The combination, with a way, a carriage, a combined traverse and hoisting rope extending along the way to and depending from the carriage, and means to control motion of that rope; of a second rope extending from said control means as a continuation of the first rope and reaching the carriage from a direction opposite to that of the first rope; a counterweight, holding taut an extensible loop in the second rope, but continuously free to rise, permitting the loop to shorten, means to stop the carriage from moving in the direction of pull of the second rope; and means to stop descent of the counterweight, whereby the loop ceases extending and the second rope pays out the carriage.

Signed by me at New York, N. Y., this 28th day of January, 1915.
